UNITED STATES PATENT OFFICE.

EDMOND M. WATKINS, OF NEW YORK, N. Y.

BASE-BALL-GAME APPARATUS.

1,269,886.

Specification of Letters Patent. Patented June 18, 1918.

Application filed March 2, 1917. Serial No. 151,969.

To all whom it may concern:

Be it known that I, EDMOND M. WATKINS, a citizen of the United States, and a resident of the city of New York, in the county of 5 Kings and State of New York, have invented certain new and useful Improvements in Base-Ball-Game Apparatus, of which the following is a specification.

The present invention relates to improvements in apparatus for playing games indoors, and more particularly to an apparatus for playing baseball upon a board that represents a baseball diamond.

The main object of the present invention 15 is to provide means whereby the game may be played with all the rules of an outdoor game, and whereby nearly all of the realistic effects may be produced.

Another object of the invention is to devise 20 an apparatus of the character described which can be manufactured on a commercial scale, or in other words one which is not so difficult to produce as to be beyond the reasonable cost of such a device.

With these and other objects in view, which will more fully appear as the nature 25 of the invention is better understood, the same consists in the combination, arrangement, and construction of parts hereinafter described, pointed out in the appended 30 claim and illustrated in the accompanying drawings, it being understood that many changes may be made in the size and proportion of the several parts and details of 35 construction within the scope of the appended claim without departing from the spirit or sacrificing any of the advantages of the invention.

One of the many possible embodiments of 40 the invention is illustrated in the accompanying drawings, in which:—

Figure 1 is a top plan view of a baseball apparatus constructed in accordance with the present invention; Fig. 2 is a section 45 taken on line 2—2 of Fig. 1; Fig. 3 is a longitudinal vertical section taken through a portion of the apparatus and the mechanical batting device in its released position, on a larger scale; Fig. 4 is a similar section 50 with the batting device in its "cocked" or operative position; Fig. 5 is a section taken on line 5—5 of Fig. 3; Fig. 6 is a top plan view, partly in section, of the detail shown in Fig. 3; and Fig. 7 is a section taken on 55 line 7—7 of Fig. 6.

The improved game comprises a rectangu-

lar board 10, provided all around with an upturned flange or railing 11, that is adapted to prevent the ball from rolling off the edge thereof. The board has leveling screws 60 12 for the well-known purpose, said screws resting upon a table or similar support. The board is covered with cloth, denoted by the numeral 10', to permit of a smooth rolling of a ball thereon. Upon the board is 65 mounted a mechanical batting device 13, the construction of which will be described hereinafter. In front of this batting device is laid out the diamond 14, and arranged just outside of the diamond and adjacent the 70 three bases are three mechanical basemen and the short-stop. These mechanical basemen and the short-stop are denoted by the numerals 15, and comprise each a substantially Z-shaped member, made of sheet 75 metal that is somewhat resilient, such as steel. The lower flange 16 of each of these members rests upon the covering of the board, and is attached to the latter by screws 17, passing through the said flange 80 into the said board. The upper flanges 18 of the mechanical fielders are slightly inclined toward the board and face the mechanical batter. The distance between the covering 10' of the board and the lowermost 85 edge of a flange 18 is somewhat smaller than the diameter of the ball used in playing the game. In rear of the four infielders above mentioned are arranged three other and larger ones, formed in a similar manner and denoted by the numerals 19. These 90 members represent the three outfielders of the game. In rear of the infielders is marked on the covering 10' an arc-shaped line 20, and in rear of the outfielders a similar line 21, for a purpose hereinafter to be 95 described. In the far off corners of the board are marked lines 22, and in the longitudinal axis of the board between the lines 22 is marked a line 23, the purpose of which 100 will be referred to when describing the operation of the device.

The mechanical batter is shown in detail in Figs. 3 to 7, inclusive, and comprises a housing 24, that is arranged in the longitudinal axis of the board, and in this housing is slidably mounted a spring-pressed plunger 25, that is provided upon its outer end with a tip 26, made of leather or a similar substance and, preferably, like those 110 of the well known billiard cues. The inner end of the plunger carries a shoulder 27,

while intermediate the ends is formed upon the plunger a stop 28, that is adapted, in the projected position of the plunger, to abut against a transverse partition 29 of the housing, thereby limiting the outward movement of the said plunger. With the shoulder 27 coöperates a sear or pawl 30, that is rigidly mounted upon a spindle 31, the latter being rotatably journaled in the sides of the housing 24. To this spindle is furthermore attached a lug 32, the free end of which is seated in a slot 33 of a lever 34, the latter being fulcrumed at 35 to the housing 24 and is under the action of a blade spring 36. Against the free end of the lever 34 bears a trigger 37, in the form of a lever that is fulcrumed at 38 to one of the railing sections 11 of the board, and disposed within a recess 39 in the said railing section. The free end of the trigger is made in the form of a knob 40, projecting above the railing section.

On the two sides of the housing 24 are disposed mechanical catches 41, similar in configuration to the mechanical fielders, they 25 being, however, mounted upon the board 10 in such a manner that they face the fielders and are adapted to arrest a ball that is rolled or thrown toward the batter from any point of the diamond 14 or from points beyond the same.

The operation of the batter is as follows: The plunger 25 is forced manually from the position shown in Fig. 3 of the drawings into the one illustrated in Fig. 4, in which 35 the sear or pawl 30 engages with the shoulder 27 on the said plunger, thereby holding the plunger "cocked" against the action of the spring 42 thereon. The spring 36 keeps, by the intermediary of the lug 32 and lever 40 34, the sear or pawl in engagement with the said shoulder. If, now, the knob 40 is depressed, the sear or pawl is disengaged from the said shoulder, which permits the spring 42 to act and to project the plunger 25. 45 From this it appears that a ball rolled manually toward the plunger 25 is adapted to be batted by the same, if the said plunger is projected or released in proper time.

To play the game on this board two persons are necessary and various rules may be established. One person, standing near the railing section 11 that constitutes the far-

thest end of the outfield, pitches manually the ball by rolling it toward the mechanical batter, and a second person controls the batter by means of the knob 40. The pitcher rolls the ball toward the plunger 25, and may readily control its direction and velocity. He is also in a position, by some practice, to pitch the ball either in a straight line 60 or a curved line to meet the plunger squarely or at its sides, thereby controlling the direction in which the ball will be batted. The person manipulating the batter, presses down the button 40 in time to meet the ball 65 pitched toward it, to project the same in the opposite direction. If a ball is batted into any one of the fielders, or comes to rest inside the line 20, the batter will be considered out, while if the ball comes to rest between 70 the lines 20 and 21, but not in any one of the fielders, the batter will be considered to have made a one base hit, and if the ball stops outside of the line 21, the batter will be considered to have made a two-base hit. 75 If the ball is batted within the line 23, a home run will be scored. If batted into the lines 22 a three-base hit will be scored. If the ball is caught by any one of the fielders it will be considered as having been 80 properly fielded and the batter as having batted out. On the sides of the batter there are two catchers, in contradistinction to the regular baseball game, where only one catcher is employed.

It is obvious that any other rules, differing from those herein mentioned, may be established for the playing of the game.

What I claim is:

An apparatus of the class described, comprising a board, and means located on said board for batting a ball, said means including a support, a spring-pressed plunger slidably mounted thereon, a sear adapted to hold said plunger in its retracted position, 90 a lug attached to said sear, a spring-pressed lever fulcrumed to said support having a slot in which said lug is seated, and a trigger bearing against said lever.

Signed at New York, in the county of 100 New York, and State of New York, this 9th day of January, A. D. 1917.

EDMOND M. WATKINS.
